UNITED STATES PATENT OFFICE

119,293

DESIGN FOR A THERMOHYDROMETER OR SIMILAR ARTICLE

Joseph T. Webber, Kalamazoo, Mich., assignor
to Roscoe B. Lacey, Kalamazoo, Mich.

Application December 11, 1939, Serial No. 88,830

Term of patent 7 years

To all whom it may concern:

Be it known that I, Joseph T. Webber, a citizen of the United States, residing in the city and county of Kalamazoo, State of Michigan, have invented a new, original, and ornamental Design for Thermohydrometers or Similar Articles, of which the following is a specification, reference being had to the accompanying drawing, forming part thereof.

The single figure of the drawing is a perspective view of a thermohydrometer embodying the invention.

I claim:

The ornamental design for a thermohydrometer or similar article, as shown.

JOSEPH T. WEBBER.
